J. LAWTON.
TROLLEY GUARD.
APPLICATION FILED APR. 10, 1912.

Patented Aug. 11, 1914.

UNITED STATES PATENT OFFICE.

JOHN LAWTON, OF IRVINGTON, NEW JERSEY, ASSIGNOR TO THE NOTWAL COMPANY, OF NEWARK, NEW JERSEY.

TROLLEY-GUARD.

1,06,823.

Specification of Letters Patent. Patented Aug. 11, 1914.

Application filed April 10, 1912. Serial No. 689,895.

To all whom it may concern:

Be it known that I, JOHN LAWTON, a citizen of the United States, residing at Irvington, in the county of Essex and State of New Jersey, have invented certain new and useful Improvements in Trolley-Guards; and I do hereby declare the following to be a full, clear, and exact description of the invention, such as will enable others skilled in the art to which it appertains to make and use the same, reference being had to the accompanying drawings, and to figures of reference marked thereon, which form a part of this specification.

15 This invention relates to a trolley guard which is mounted on the end of the trolley-pole adjacent to the trolley-wheel and is of the type that has projecting fingers or fenders to engage the trolley wire if the trolley-wheel jumps down from the wire due to strain or shock, or if the trolley is going around a curve, causing a transverse strain on the wheel and the wire.

20 The invention comprises a device of this class in which the guard is adapted to freely swing, but normally being in a position where the arms project vertically to engage the wire, the arms, however, giving way freely if the arms meet an obstruction, such as a cross wire, a support, or the projecting portion of a switch.

25 The invention is further designed to provide a guard of this type in which, when the fingers swing downward, studs on the guard are brought into position to engage the wire, these studs not projecting as far from the guard as the arms.

30 Another feature of the invention is a stop which engages the wire to transmit the current, but at the same time acts to limit the swing of the guard so that it will not swing too far. The device is held in its normal position preferably by gravity.

35 The invention is illustrated in the accompanying drawing, in which—

Figure 1 is a side view of a trolley with the guard attached, the guard being shown in dotted outline in two different positions. Fig. 2 is a front view of Fig. 1. Fig. 3 is 40 a vertical section through the center of the trolley-wheel.

45 Any usual form of trolley pole 10 is used on which is mounted a suitable support 11 having the divided arms 12, the ends of the 50 arms acting to support a spindle or shaft

13, the nuts 14 acting to lock the spindle in place. The spindle is provided on one side with a shoulder 15, and on the other end, that is, on its threaded end, with the bearing nut 16. Between the bearing nuts is 60 mounted the guard which consists of side-plates 17 and 18, and between these side-plates, the collar 15 and the bearing nuts 16 are the ball-bearings 19. Between the side-plates 17 and 18 of the guard is the 65 trolley-wheel 20 having a central groove 21. Between the sides of the trolley-wheel and the side-plates of the guard are the ball-bearings 22 which preferably run on a steel bushing 23 within the trolley-wheel whereby the trolley-wheel lasts longer 70 because its bearings being of steel will resist wear much longer than the usual all-brass wheel. The guard is recessed on its side-plates as at 24 to receive the sides of 75 the trolley-wheel so that the only part exposed to the wire is the groove 21. The lower portion 25 of the guard is weighted, that is, it is made heavier than the balance 80 so that this portion normally points downward, the side-plates at the bottom portion being connected by a bolt 26 fastened by the nuts 27 and supporting a suitable roller 28. The arms 12 are long enough to allow the weighted portion 25 of the guard to swing 85 forward between the arms and beyond them.

Projecting upwardly from the side-plates and being normally vertical on account of the weighted portion holding the guard in its proper position, are the arms 29 which 90 may be made slightly divergent and have their inner faces 29* rounded. The arms 29 have fenders 30 to assist in finding the wire when necessary. On the front of the side-plates are the studs 31 which do not project 95 as far from the side-plates of the guard as the arms 29.

To facilitate the assembling of the parts one of the arms 12 is made of two pieces as shown in Fig. 1 and at the right hand side 100 in Fig. 2, the two members of the arm being designated by the reference numerals 32 and 33, these members being cut away to permit them to be fitted together to make flush inner and outer faces, and being held together by bolts 34 fastened by suitable nuts 35. This facilitates the removal of the member 32 of the arm, and then by loosening the nut 14 at the other end of the spindle, the 105 spindle and the wheel, along with the guard, 110

can be withdrawn together. This provides a quick means for taking out a trolley-wheel and also allows of a correspondingly quick installation of a new wheel or the return of 5 an old one. A suitable duct 36 is provided for oiling purposes.

The trolley-pole is handled by means of a rope or similar device as at present, and when the trolley is in the position shown in 10 Fig. 1 and is moving forward, the wire is inclosed by two comparatively high walls on each side formed by the sides of the groove in the trolley-wheel and by the arms 29 on each side thereof. If the arms 29 meet an 15 obstruction, such as a cross wire, or any projection on a wire, the arms are pushed back and the guard swings freely on its bearings to the position shown at *a* in Fig. 1, and the studs 31 are then swung to a position flanking 20 the wire, whereby the wire is engaged both to the rear and to the front of the center of the spindle on which the trolley-wheel is rotating to doubly insure the "tracking" of the wheel on the wire.

25 If the car is going at high speed when the arms 29 are engaged, they are swung down with some force to the dotted position shown at *b* in Fig. 1, which throws the studs 31 slightly to the rear of the center of the trolley-wheel and causes the stop 28 to engage 30 the under side of the trolley wire to limit the swing of the guard. When the guard is so limited in its motion it quickly returns to its normal position, and at any point in the 35 swinging of the guard it will be noted that either the guard, the studs or the weighted portion of the guard are flanking the trolley

wire in addition to the groove in the trolley wheel.

Having thus described my invention, what 40 I claim is:—

1. A trolley comprising a freely swinging guard having side plates and arms normally projecting vertically therefrom and said plates each having a weighted lower portion, 45 a stop connecting the weighted lower portions of the side plates, the lower portions being wide so as to form guards extending above the trolley wire when the said plates are swung to cause the engagement of the 50 stop with the trolley wire, the stop being arranged at a distance from the bottom, a trolley wheel between the side plates; and a support for the wheel and guard and constructed to permit the guard to swing freely. 55

2. A trolley comprising a guard consisting of side plates, the side plates having vertically projecting arms at the top and having weighted lower portions, a stop connecting the lower portions and being arranged to 60 engage a trolley wire when the guard is swung, the weighted portions being made wide and long to extend a considerable distance to all sides of the stop, whereby when the stop engages the trolley wire, the 65 weighted portions extend above the trolley wire and act as a guard.

In testimony, that I claim the foregoing, I have hereunto set my hand this 6th day of April 1912.

JOHN LAWTON.
